UNITED STATES PATENT OFFICE.

ABRAHAM M. DAVIS, OF CHICAGO, ILLINOIS.

ADJUSTABLE WALL BRACKET.

Application filed September 11, 1926. Serial No. 134,908.

This invention relates to wall brackets which are adapted for various purposes, such as supporting electric fans, bric-a-brac, vases or the like.

5 The objects of this invention are to provide an improved wall bracket for the purposes indicated which will be of unique construction and ornamental in appearance; to provide a wall bracket which may be suspended from a molding; to provide a bracket having an adjustable shelf; to provide a wall bracket having a fixed portion and an adjustable portion with concealed adjusting or connecting members; and to provide 10 such other novel features and improvements as will be described more fully hereinafter.

In the accompanying drawings showing a preferred form of my invention;

20 Figure 1 is a front view showing the bracket supported on a molding;

Figure 2 is a sectional view taken on the line 2—2 of Figure 1;

Figure 3 is a sectional view taken on the line 3—3 of Figure 1; and

25 Figure 4 is a detail showing the fastening or adjusting devices.

In the particular form of the invention as shown in these drawings, the fixed or stationary portion of the bracket comprises side strips or bars 5 which are rigidly secured together at the bottom by cross boards 6. The front or forward surfaces of these boards are preferably made flush with the faces of the side strips, although such boards 30 may be panelled or ornamented if desired. The upper ends of the side strips are provided with hooks 7 which are secured to the strips in any desired manner, as by means of screws 8. These hooks are preferably 35 made to conform more or less closely with the outline of the molding or supporting member 9 with which they are intended to engage and are preferably offset or bent, as shown in Figure 2 so that the bracket will 40 fit closely against the wall 10.

The supporting shelf 11 is secured to a board or plate 12 and is preferably braced by means of a combined brace and handle member 13. The plate or board 12 fits 45 against the front face of the stationary part of the bracket and is provided with catches or fasteners 14 which engage with pins or supporting members 15 on the inner edges of the strips 5. The catches 14 are preferably 50 made in the form of angles, as shown in Figure 4, with slots 16 for receiving the pins

15. The inner edges of the slots are preferably bevelled, as shown at 17, and the pins are so positioned that they will engage with such bevelled edges in order to draw 60 the board 12 tightly against the face of the stationary bracket member.

A plurality of the oppositely disposed pins 15 are provided in order to give any desired vertical adjustment for the shelf. 65 When the shelf is to be adjusted, the brace 13 serves as a handle so that the bracket and the board 12 may be readily raised to disengage the fasteners from one set of pins and then moved up or down to bring the fasteners into engagement with another set of pins 70 as desired.

From this description it will be seen that I provide a bracket or supporting device which may be readily hung on a molding or similar 75 supporting member and will hang closely against the wall. Furthermore, the shelf may be quickly and easily adjusted for supporting a fan or the like at any desired height within the range of adjustment. It 80 will of course be evident that my improved bracket may be made in various designs or forms without departing from the scope of the invention; therefore I do not wish to be limited to the exact arrangement herein 85 shown and described, except as claimed in the following claims, in which I claim:

1. An adjustable bracket comprising a pair of side strips, boards connecting the lower ends of the strips, hooks secured to the 90 upper ends of the strips, a plurality of oppositely disposed pairs of pins on the inner edges of the strips, a plate or board extending across the strips and engaging with the faces thereof, fasteners on the plate for 95 engagement with said pins, and a shelf on said plate.

2. An adjustable wall bracket comprising a plate, a shelf secured to said plate, a combined bracket and handle secured to the 100 shelf and plate, a pair of strips, means for securing the strips together, a plurality of pins in said strips, and fasteners on said plate having bevelled edges for engagement with the pins for drawing the plate against 105 the strips.

3. In a device of the character set forth, the combination of a relatively fixed member having a plurality of supporting pins, an adjustable member, fasteners on said adjustable member having slots for engagement with the pins, said slots having bevelled 110

edges for drawing the adjustable member against the fixed member, substantially as described.

4. A bracket comprising a pair of strips having hooks on their upper ends, means for securing the strips together, pins on said strips, a plate, hooks on said plate for engagement with said pins, a shelf secured to said plate, and a combined handle and brace 10 engaging with the shelf and the plate.

5. A new article of furniture for supporting electric fans or the like, comprising two vertical strips which are rigidly secured to-

gether at their lower ends by means of suitable cross pieces, means for attaching the 15 upper ends of the strips to a molding or the like, a plurality of fastening members on said strips, a plate extending across said strips and engaging with the front thereof and having fasteners at approximately the 20 vertical center thereof which engage with the fastening members on the strips and tend to draw the plate against the strips, and a shelf carried by said plate.

ABRAHAM M. DAVIS.
